COVER FOR A HYPODERMIC SYRINGE PACKAGE

John E. Thomas, Matteson, Ill., assignor to Armour Pharmaceutical Company, Phoenix, Ariz.

Filed Jan. 21, 1974, Ser. No. 435,069

Term of patent 14 years

Int. Cl. D9—03

U.S. Cl. D9—192

FIG. 1 is a perspective view of a cover for a hypodermic syringe package showing my new design;

FIG. 2 is an enlarged scale cross-sectional view taken along line 2—2 of FIG. 1; and

FIG. 3 is a bottom perspective view thereof.

I claim:

The ornamental design for a cover for a hypodermic syringe package, as shown and described.
